UNITED STATES PATENT OFFICE

155,917

DESIGN FOR A BRUSH AND COMB HOLDER

Orley B. McCarty, East Cleveland, Ohio

Application October 3, 1947, Serial No. 141,735

Term of patent 3½ years

(Cl. D86—10)

To all whom it may concern:

Be it known that I, Orley B. McCarty, a citizen of the United States, residing at East Cleveland, in the county of Cuyahoga and State of Ohio, have invented a new, original, and ornamental Design for a Brush and Comb Holder, of which the following is a specification, reference being had to the accompanying drawings, forming a part thereof.

I claim:

The ornamental design for a brush and comb holder, as shown.

ORLEY B. McCARTY.
